[57] CLAIM

The ornamental design for a waste collecting receptacle, as shown and described.

DESCRIPTION

FIG. 1 is a top and front perspective view of a waste collecting receptacle showing my new design;

FIG. 2 is a front elevational view thereof;

FIG. 3 is a rear elevational view thereof;

FIG. 4 said side elevational view thereof, the opposite side elevational view being a mirror image of the shown;

FIG. 5 is a top plan view thereof; and,

FIG. 6 is a bottom plan view thereof.

FIG.1.

FIG. 2

FIG. 4.

FIG. 3.

FIG. 5.

FIG. 6.
